ELECTRONIC SWITCH

J. Ernest Smith, Jackson Heights, and Eugene R. Shenk, Brooklyn, N. Y., assignors to Radio Corporation of America, a corporation of Delaware

Application September 18, 1942, Serial No. 458,808

11 Claims. (Cl. 250—27)

This invention relates to an electronic switch. In a variety of applications it is found to be advantageous to perform switching operations by means of controlled electron discharge tubes. The invention as herein described performs such a switching operation equivalent to that of a double-pole double-throw switch.

It is an object of our invention to provide an electronic switch capable of performing a dual switching function in response to the application of an on-and-off current in a control circuit.

It is another object of our invention to provide switching means for interchanging the connections between two input circuits and two output circuits.

It is still another object of our invention to provide a reversing switch operable upon the respective inputs of two signaling channels so as to feed these inputs after amplification reversibly to two independent output channels.

Our invention may best be described by reference to the accompanying drawing, the sole figure of which represents diagrammatically a preferred embodiment.

In the drawing we show conventionally two input circuits A and B; also two output circuits C and D. A control circuit E is indicated as having one grounded terminal and one terminal the potentials of which are used by capacitive coupling across a condenser to the control grid of a discharge tube 2.

We show also two amplifier tubes 3 and 4 which are preferably of the twin triode type. A direct current source 5 supplies the necessary D. C. potentials for operating the three tubes 2, 3, and 4.

The input circuit A is coupled across a transformer 6 to control grids 7 and 8, these control grids being included in the tubes 3 and 4 respectively. The input circuit B is coupled across transformer 9 to control grids 10 and 11 which are individual to the tubes 3 and 4 respectively.

The common cathode 12 in tube 3 is connected to a junction between two resistors R1 and R2. The common cathode 14 in tube 4 is connected to the cathode 15 in tube 2 and both these cathodes are connected through a resistor R3 to ground and to the negative terminal of source 5.

Across the terminals of source 5 is connected a voltage divider consisting of resistors R4, R2, and R1. The junction between resistors R4 and R2 is tapped for feeding potential to the anode in tube 2. The control grid 16 in tube 2 is provided with a grid leak resistor R5 connected to ground.

The tube 3 possesses two anodes 17 and 19 while the tube 4 possesses two anodes 18 and 20. 55

The anodes 17 and 18 are connected in parallel and are fed with anode potential through the primary winding of a transformer 21. The secondary of this transformer feeds output signal potentials to the channel C.

Anodes 19 and 20 are connected in parallel and both are fed with anode potential through the primary winding of transformer 22. The secondary of this transformer is connected to the output channel D.

15 The control tube 2 is rendered alternately conductive and non-conductive by virtue of a square type voltage control signal impressed on the terminals E. By means of this control tube 2, the tubes 3 and 4 are rendered alternately conductive. When tube 3 conducts, then tube 4 is blocked and vice-versa.

20 In order to perform the switching functions satisfactorily, it is found that certain circuit parameters should be obtained, particularly in reference to the impedance values of the resistors R1, R2, R3, and R4 in relation to the impedance, R_p, of the tube 2 when it is conductive. Optimum results are obtained when the circuit relations are as follows:

$$\begin{aligned} R1 &= 2R3 \\ R2 &= 2R_p \\ R4 &= R1 + R2 = 2(R4 + R_p) \end{aligned}$$

30 A repeating square-wave applied to the grid 16 in tube 2 then causes tubes 3 and 4 to alternately conduct and block the passage of signals applied to their grids. A conductive state in tube 3 is established by rendering tube 2 conductive. This fact will be evident when it is seen that the cathode potential in tube 3 is substantially reduced by the shunting of a certain amount of current through the tube 2, thus increasing the potential drop through resistor R4. The current in resistors R2 and R1 is correspondingly reduced and the voltage on cathode 12 approaches ground potential. Under this condition, the signals from channel A are amplified in the upper section of tube 3 and are passed out on channel C. At the same time signals derived from the input channel B are amplified in the lower half of tube 3 and are passed out on channel D.

40 During the conductive state of tube 3, tube 4 is blocked by a considerable voltage drop in resistor R3, the cathode resistor for tube 2. Tube 2 when it is conductive has a relatively positive cathode in respect to ground potential and, therefore, the cathode 14 in tube 4 stands at a sufficiently positive potential with respect to its grids 8 and 11 so that this tube cannot conduct.

Assuming now that the signal potential in the control circuit E is such as to apply a negative bias to the grid 16, then tube 2 becomes blocked. Now the cathodes 15 and 14 are substantially reduced to ground potential so that tube 4 becomes conductive. The signals applied by input channel A to the grid 8 and by input channel B to grid 11 become effective in tube 4 for amplifying and delivering these respective input signals in such manner that output channel C takes the signal input from channel B, and output channel D takes the signal input from channel A. While this condition persists, that is, a conductive state in tube 4, tube 3 is blocked by virtue of the relatively positive potential applied to its cathode 12 with respect to ground. This will be observed from the fact that with tube 2 blocked, the voltage drop through resistors R4, R2, and R1 is such as to maintain the desired positive potential on the cathode 12. The grid potentials in the tubes 3 and 4 do not fluctuate with respect to ground other than in response to the signal voltages derived from the action of transformers 6 and 9.

It will be apparent that the double-pole double-throw switching function may be carried out in the above manner as often as may be desired, and either at regular or irregular intervals, all depending upon the nature of the train of signals applied to the terminals E. In certain applications, the switching operation may need to be performed very rapidly and under control of the half cycles of an alternating current, either of very high frequency or of medium high frequency. On the other hand, the switching may be accomplished by means of a manual key in the circuit E, or it may be accomplished by a perforated tape transmitter such as is used in Morse telegraphy. Other control means may also suggest themselves to those skilled in the art.

It will be noted that our improved switching system possesses no time constant circuits such as might interfere with the on-and-off holding time for the tubes 3 and 4. In other words, the switching function may be performed independently of any time constants inherent in the circuit itself. The switching is substantially instantaneous and is inertialess.

The applications of our invention to communications systems, and other electrical systems as well, are too numerous to mention. The scope of the invention should, therefore, be considered as broadly covering a great variety of such applications.

We claim:

1. A plurality of electron discharge devices having a total of four discharge paths and constituted as a double-pole double-throw reversing switch, said devices having cathode grid and anode electrodes, means including a discharge tube for so controlling the bias potential applied between the cathodes and control grids of said devices that conductivity is obtained in two of said paths as selected while the two remaining paths are blocked, and means including an input potential source applied to said discharge tube for interchanging the control effects of the first said means.

2. The combination according to claim 1 and including two independent input channels and two independent output channels coupled to the input and output sides respectively of said discharge devices.

3. In an electronic switching arrangement of the double-pole-double-throw type, a pair of in-

dependent input circuits A and B, a pair of independent output circuits C and D, controllable electronic amplifier means for feeding signals from each of said input circuits simultaneously to a respective one of said output circuit, and bias control means effective to render different portions of said amplifier means interchangeable conductive and non-conductive, one portion of said amplifier means being arranged, when it is conductive, to direct signals from input circuit A to output circuit C while also directing signals from input circuit B to output circuit D, the other portion of said amplifier means being arranged, when it is conductive, to direct signals from input circuits A and B into output circuits D and C respectively.

4. An electronic switching arrangement of the double-pole double-throw type comprising two independent input circuits, two independent output circuits, two discharge tubes of the twin triode type, parallel connections from one of said input circuits to certain control grids, one in each of said tubes, parallel connections from the other of said input circuits to the remaining control grids in said tubes, each of said output circuits having parallel connections to appropriate anodes in both tubes, a direct current operating potential source having impedance connections to the electrodes of said tubes, and means including a controlled discharge device the space path in which completes a potentiometer shunt circuit across the terminals of said source for producing a reversible voltage difference between the cathode of one tube and that of the other, whereby signals delivered by each input circuit are simultaneously and independently transferred to a selected one of said output circuits.

5. The method of performing an electronic reverse switching operation as between each of two independent input circuits and each of two independent output circuits, alternative space discharge paths being provided whereby signals delivered by each input circuit are amplified in one or the other of said output circuits, which method comprises causing a control voltage of substantially square-wave formation to be amplified in still another discharge path, utilizing the transconductance of the last mentioned discharge path to differentiate between cathode potentials in respect to the discharge paths first mentioned, causing the more positive of said cathode potentials to block two of said discharge paths, and causing the more negative of said cathode potentials to render the remaining discharge paths conductive.

6. In a double-pole double-throw electronic switching arrangement comprising alternative space discharge paths for coupling each of two input circuits interchangeably to each of two output circuits, switching control means responsive to a control voltage of substantially square wave formation, said means comprising a discharge tube the space path of which constitutes one arm in a Wheatstone bridge circuit, a resistor of predetermined value in each of the other arms of said bridge circuit, a direct current operating potential source for said switching arrangement and for said tube, said source having its positive terminal connected through a fixed impedance to one corner of said bridge circuit and having its negative terminal connected to the opposite corner thereof, said switching arrangement having connections from points of cathodal potential therein to the remaining two corners of said bridge circuit, and connections from the positive ter-

inal of said source to points of anodal potential in said switching arrangement.

7. The combination according to claim 6 and including control grids in the discharge paths of said switching arrangement, two of said grids in alternatively conductive paths being parallel-connected in coupling relation to one of said input circuits and two remaining grids being similarly connected in coupling relation to the other of said input circuits.

8. An electronic double-pole double-throw switch in combination with an electronic control device therefor, said device comprising a discharge tube responsive to control potentials of square wave form, a direct current operating potential source for said switch and said control device, input circuits A and B and output circuits C and D, two discharge paths in said switch having control grids responsive to signals derived from circuit A and having anodes independently coupled to circuits C and D, two remaining discharge paths in said switch having control grids responsive to signals derived from circuit B and having anodes each in parallel with one of the aforesaid anodes respectively, and means including resistive elements connected between the terminals of said source and cooperating with said discharge tube for causing a reversal of conductive states as between one pair and another pair of discharge paths in said switch.

9. In a device of the class described, two input signal channels A and B, two output signal channels C and D, and a square wave switching control source E, electron discharge switching means having cathode, anode and grid electrodes, and having at least two envelopes, separately enveloped grids being interconnected in pairs and

each pair thereof being coupled to a respective one of the channels A and B, separately enveloped anodes which are opposed to grids of different pairs being connected in parallel and coupled to a respective one of the channels C and D, a bridge circuit including resistive impedances in three arms and a discharge tube in the fourth arm, a source of direct current operating potential for said switching means and for said tube, 5 a potentiometer circuit connected across the terminals of said source and including a resistor in series with said bridge, and means including connections from each branch of said bridge respectively to the separately enveloped cathodes 10 in said switching means for producing selective emission therefrom in dependence upon the control of said discharge tube by potentials from the source E.

10. Switching apparatus for reversing the 20 channels of communication between two input circuits A and B and two output circuits C and D, said apparatus including a twin triode discharge tube two discharge paths in which are commonly controllable for simultaneously passing signals 25 from circuit A to circuit C and from circuit B to circuit D, a second twin triode discharge tube two discharge paths in which are commonly controllable for simultaneously passing signals from circuit A to circuit D and from circuit B to circuit C, and selective means responsive to control 30 impulses for applying a cut-off bias to one of said tubes while producing emission in the other.

11. Switching apparatus according to claim 10 and including a bridge circuit in said selective 35 means, and a discharge tube in one arm of said bridge circuit.
